[57] CLAIM

The ornamental design for a foot massager, as shown and described.

DESCRIPTION

FIG. 1 is a top, front, right-side perspective view of a foot massager showing my new design, the left side view being symmetrical to the right side view;

FIG. 2 is a rear, top perspective view thereof;

FIG. 3 is a front, top perspective view thereof;

FIG. 4 is a top front perspective view thereof taken from a different angle from that of FIG. 3 but with the cover swung up;

FIG. 5 is a top view thereof with the cover in its open position; and,

FIG. 6 is a bottom view thereof.
